UNITED STATES PATENT OFFICE.

VIRGIL H. CAIN, OF ATLANTA, GEORGIA.

CARD OR LABEL HOLDER FOR THE HOME ROUTING OF CARS.

SPECIFICATION forming part of Letters Patent No. 769,375, dated September 6, 1904.

Application filed September 27, 1902. Serial No. 125,084. (No model.)

To all whom it may concern:

Be it known that I, VIRGIL H. CAIN, a citizen of the United States, residing at Atlanta, in the county of Fulton and State of Georgia, 5 have invented new and useful Improvements in Card or Label Holders for the Home Routing of Cars, of which the following is a specification.

The invention aims to provide a new and 10 novel holding device hereinafter more specifically referred to and which is adapted for holding labels or cards which are adapted to be employed for indicating the lines of railways over which a car travels and also to indicate the names or the junction-points at 15 which the car may be transferred, as well as the dates of the transfer.

The invention further aims to provide a 20 card or label holder for the home routing of cars which shall be simple in its construction, strong, durable, efficient in its use, and comparatively inexpensive to manufacture.

In describing the invention in detail reference is had to the accompanying drawings, 25 forming a part of this specification, wherein like reference characters denote corresponding parts throughout the following views, in which—

Figure 1 is an elevation of the card-holder. 30 Fig. 2 is a vertical sectional view thereof, showing several cards in position. Fig. 3 is a sectional view on line 6-6 of Fig. 1, and Fig. 4 is a section on line 7-7 of Fig. 1.

The card or label holder consists of a 35 rectangular flat plate of suitable material 20, having its top bent to form a gutter 21, constructed of any suitable shape. The plate is bent upon itself at its lower end to form a flange 22. The flange 22 extends approximately across half of the lower portion of the plate. Secured to the outer face of the plate 40 is a pair of vertically-extending strips of material 23, substantially L-shaped in contour and suitably spaced apart. The plate 45 at its lower end is bent upon itself to form a flange 24, between the strips of material 23. The strips 23 and flange 24 form a pocket the function of which will be hereinafter referred to. Secured to the outer 50 face of the plate 20 and in vertical alinement

with the flange 22 is a strip of material 25, which is bent parallel with the plate. The strip 25 and flange 22 form a pocket the function of which will be hereinafter referred to.

Secured to the front of the plate 20 is a 55 pair of laterally-extending strips of suitable material 26, having their lower ends beveled, as at 27. The strips 26 are suitably spaced apart and preferably have their lower ends engage the strip 25, although this is not necessary, as the ends of the strips 26 may be above the strip 25. The strips 26 have connected to their beveled ends an inwardly-extending flange 28. The tops of the strips 26 are connected together by the wire rod 29, 60 the ends of this rod 29 being suitably connected to the strips 26. The reference character 30 denotes a stay-rod which is connected at its upper end to the rod 29 and at its lower end suitably connected to the plate 20. 65 The lower end of the rod 30 is bent at an inclination, so it will be substantially of the same contour as the beveled ends of the strips 26. Pivotally mounted upon the rod 29 is a 70 card guide or retainer having its inner end extending downwardly at an inclination, as at 31, and its outer end weighted, as at 32. The guide is pivoted to the rod 29, as at 33. The strips 26, flanges 28, and rod 30 are adapted 75 to form a pocket to receive the indicating cards 34. The inclined portion 31 of the card guide or retainer is adapted to engage the cards and hold them within the pocket, as well as guiding each card to the front as it is placed into the pocket, so that the card will appear in 80 full view. The cards are retained in the pocket by the guide, owing to the weighted end of the card-guide, which retains the inclined portion of the guide always against the cards. The flanges 28 and rod 30 are also 85 adapted to assist in retaining the cards within the pocket. Owing to the sloping bottom of the pocket the cards are retained therein in such manner that one will project above the other, so that when it is necessary to remove the front card it can be easily grasped 90 by an employee of the railroad.

The pocket formed by the strips 23 and flange 24 is adapted to receive the defect and repair cards for the car, and the pocket formed 100

by the strip 25 and flange 22 is adapted to receive the penalty-card, trackage-slip, or other special cards.

Having thus fully described my invention, 5 what I claim as new, and desire to secure by Letters Patent, is—

1. Means for home routing railway-cars comprising a holder for cards, said holder provided with a pocket to receive the card and 10 a combined guide and retainer for the cards having its inner end extending in the mouth of the pocket and engaging the front face of the outer card.
2. Means for home routing railway-cars

comprising a holder for the cards, said holder 15 provided with a card-pocket having an open front wall and a combined guide and retainer for the cards having its inner end extending in the mouth of the pocket and engaging the front face of the outer card.

In testimony whereof I have hereunto set my hand in presence of two subscribing witnesses. 20

VIRGIL H. CAIN.
